UNITED STATES PATENT OFFICE.

ISAAC W. DRUMMOND, OF NEW YORK, N. Y.

PAINT-MIXER.

SPECIFICATION forming part of Letters Patent No. 624,632, dated May 9, 1899.

Application filed January 4, 1899. Serial No. 701,099. (No model.)

To all whom it may concern:

Be it known that I, ISAAC W. DRUMMOND, a citizen of the United States, and a resident of the borough of Manhattan, in the city of New York, county and State of New York, have invented certain new and useful Improvements in Paint-Mixers, of which the following is a specification.

In the use of paint-mixers, or, as sometimes called, "dipping-machines," the difficulty is encountered that when the apparatus is unused for a time—as, for instance, over Sunday or during a holiday and in some instances even for so short a period as overnight—the pigment will precipitate through the oil or equivalent liquid, depositing itself upon the bottom or lower portions of the tank and upon the mixing apparatus usually there located, and before the use of the apparatus can be resumed it is necessary that the pigment be in some way again uniformly distributed through the mass of oil or equivalent liquid. This is sometimes a difficult matter to accomplish, because certain pigments, particularly if allowed to remain in their precipitated condition for any considerable length of time, acquire such a degree of solidity that it is difficult for the mixers to stir or break them up, and thus make the contents of the tank homogeneous.

The purpose of my invention, therefore, is to afford means whereby the pigment as it precipitates will fall upon what may be called a "two-part" false bottom located within the tank and above the stirring or mixing devices, the construction being such that both of these parts have openings through them, and one of them is adapted to move relatively to the other after the fashion of an ordinary draft-regulator in stoves, so that when the movable part is in one position its solid or closed portions overlap the open portions in the other or stationary part, and when in its other position the solid or closed parts of both register with each other, so that openings through them both are produced.

The invention likewise contemplates so constructing and arranging the movable part that it shall during its movement over the other or stationary part sheer off or remove the pigments which have been deposited by precipi-

tation upon it, so that when the agitator is put in operation the liquid in the tank will be forced by it upwardly through the openings in the two plates composing the false bottom and in so doing violently agitate and remix the pigments which have been broken up and loosened from their resting-places by the movement of one part of the false bottom over the other.

The invention also includes certain details of construction, which will hereinafter be pointed out.

Referring to the drawings hereof, Figure 1 illustrates a longitudinal vertical sectional view of one form of my apparatus, taken on the line 2 2 of Fig. 2. Fig. 2 illustrates a plan view of the apparatus shown in Fig. 1. Fig. 3 shows a detail in perspective.

A illustrates the tank. It is usually made of boiler-iron, but may be made of any suitable construction and of any desired form and dimensions.

B is a shaft journaled at or near its opposite ends in or upon the walls of the tank.

C C are rotary mixing-blades fast on the shaft.

D is a stuffing-box through which the shaft passes at one end and whereby leakage of the liquids is prevented.

E is a driving-pulley, and F a driving-belt.

I show a single shaft with propeller-blades or mixers and associated mechanism, and it is located in the central line of the tank. I wish it distinctly understood, however, that this form of mixer is shown merely as an example of one form of suitable apparatus. There are a large number of devices, some of them resembling that shown by me and some embodying a series of pipes, with a pump whereby the liquid is jetted from holes or nozzles in the pipes; also, oscillating paddles and similar devices may be used for the purpose of agitating the liquid, and if a shaft with propeller-blades such as shown by me is used there may be two or more of them in the bottom of the tank to more completely agitate its contents, or the bottom of the tank may be made semicircular in shape, and a shaft having larger propellers or mixing-blades substantially coinciding in size with the semicircular bottom of the tank may be

employed. In other words, I do not limit myself in any respect as to this feature of the apparatus.

Above the mixing or agitating devices, 5 whatever they may be, the false bottom referred to by me is placed. It is composed of two parts. One of them, G, is stationary and comprises side sections and cross-sections having open spaces H between them, the area 10 of which is substantially the same as the cross-sections G between them, although preferably slightly less in width. This frame is supported on its edges and ends by suitable sustaining devices such as the brackets 15 I on the tank. The other or movable part of the false bottom is superposed upon the stationary part just described and is composed of a lateral frame K, having cross sections or pieces K', somewhat resembling elongated saw-teeth—that is to say, they project upwardly from the frame K, and one of their sides is inclined (to the left in this drawing) and the other side is or may be vertical. The arrangement is such that these sections K' 20 when the frame is moved to the right, as shown in Fig. 1, will cover and close the openings H in the lower or stationary plate, the front or sheering edges of the inclined surfaces of the projections K' resting upon the 25 cross-sections G of the stationary part adjacent to the edge of the openings between them. L is a shaft or equivalent device rigidly attached to the movable part of the frame, which passes outwardly through the wall of 30 the tank through a stuffing-box M and is threaded on its outer end N, on which a hand-wheel O, which has a threaded hub P, engages. The hand-wheel is held against movement in either direction by arms Q, which engage with 35 a groove on the casing of the stuffing-box, as shown, so that rotary movement is permitted the hand-wheel O, but not longitudinal movement in either direction.

The operation of the apparatus is as follows: At the time the use of the apparatus ceases the hand-wheel O is turned in such manner that the movable upper frame K K' is moved to the right, so that the cross-sections K' cover the openings H in the lower or 40 stationary part. Of course the mixer B C is put at rest. While the parts are in this position the pigments precipitate, settling in the liquid (shown at X) and deposits itself upon the exposed parts of the false bottom. When 45 it is desired to resume work, the mixers or stirrers are started, and at the same time the hand-wheel is operated in such manner as to slide the movable half of the false bottom to the left. In its transit it sheers off the 50 pigments which have deposited upon the cross-sections G of the stationary part, during which operation the pigment crowds upon that which has been deposited upon the inclined surface of the projections K', likewise 55 breaking it up, and as soon as the movement of one of the parts over the other produces

slits or openings through the false bottom the liquid, which is violently agitated by the mixer, spurts upwardly through such openings and continues so to do until the movable 70 part has completed its movement, by which time practically all of the deposited pigment has been carried upwardly into the tank above the false bottom and mixed with the oil or other liquid under the stated action of 75 the agitator or mixer, so that a continuance of the operation of the agitator for a short time will thoroughly reincorporate the pigment with the liquid, making the contents of the tank homogeneous. Thereupon the work 80 of dipping the articles to be coated proceeds as usual. The agitator is from time to time (or in some instances continuously) run at a relatively slow speed to maintain the mixture in a condition of homogeneity. 85

It will be noted that one side of the upwardly-projecting sections K' is made practically vertical. This is so that there will not be any precipitation of the pigments upon that surface, since there is nothing excepting the swash of the liquid to break it up or remove it should it be deposited thereon. I therefore prefer the construction shown. I also sometimes prefer to make the cross-sections G of the stationary lower frame pointed 90 transversely on their lower surfaces, as shown by dotted lines R R, &c. This is so the liquid which is forced upwardly by the agitators may impinge against the inclined surfaces referred to and guide upwardly through 95 the openings in the false bottom, thus preventing reverse currents and conduced to the upward rush of the liquid through said openings.

I wish it distinctly understood that I do 100 not limit myself to any of the above-recited details. They are in my opinion valuable features in an apparatus of this character; but it will be obvious to those who are familiar with such apparatus that a number of 105 changes may be made without departing from the essentials of the invention. For instance, the upper plate, K K', may be stationary and the under one, G, movable. Also a lever suitably arranged may be employed instead of a 110 hand-wheel, and it may be located entirely within the tank, so as to avoid the necessity for a stuffing-box, &c. Also the shape and relative dimensions of the cross-sections K' and 115 G of the two frames may be varied from that shown. I therefore do not limit myself to any of the details shown, the essential feature 120 of my improvement being that there shall be a two-part false bottom located above the mixing devices whatever their construction 125 may be, both parts of the false bottom being perforated and one or both of them movable, so that the perforations may be made to register and non-register with each other for the purposes stated, and that as they pass over 130 one another the pigment deposited upon them may be dislodged and moved into such posi-

tion that it will be subjected to the currents generated by the mixer or mixers.

Having described my invention, I claim—

- 5 1. The combination, in a paint-mixer, of a tank, agitating or mixing devices, a two-part false bottom located above the mixing devices, each part being perforated, and means to move one of the parts, for the purposes set forth.
- 10 2. The combination, in a paint-mixer, of a tank, agitating or mixing devices, a two-part false bottom located above the mixing devices, each part being perforated in such manner that the perforations may be made to register with each other, and means to move one of the parts, for the purposes set forth.
- 15 3. The combination, in a paint-mixer, of a tank, agitating or mixing devices, a two-part false bottom located above the mixing devices, each part being perforated, the two parts resting upon each other in such manner that one will sheer across the surface of the other, and means to move one of the parts, for the purposes set forth.
- 20 4. The combination, in a paint-mixer, of a tank, agitating or mixing devices, a two-part false bottom located above the mixing devices, each part being perforated, the upper part having cross-sections between the perforations the sides of which are at an angle to the axis of the part as a whole, and means

to move one of the parts, for the purposes set forth.

5. The combination, in a paint-mixer, of a tank, agitating or mixing devices, a two-part 35 false bottom located above the mixing devices, each part being perforated, the cross-sections of the lowermost part having downwardly-presented angular sides whereby the currents generated by the mixer will be deflected upwardly through the openings, and means to move one of the parts, for the purposes set forth.

6. The combination, in a paint-mixer, of a tank, agitating or mixing devices, a two-part 45 false bottom located above the mixing devices, each part being perforated, the sections of the upper part which lie between the perforations being angular and having an upward presentation and the sections between 50 the perforations of the lower part being angular and having a downward presentation, and means to move one of the parts, for the purposes set forth.

Signed at New York, in the county and 55 State of New York, this 30th day of December, A. D. 1898.

ISAAC W. DRUMMOND.
